VALVE STRUCTURE

William R. Brown, Chicago, Ill., assignor to W. R. Brown Corporation, Chicago, Ill., a corporation of Illinois

Original application January 11, 1943, Serial No. 472,020. Divided and this application April 7, 1944, Serial No. 529,898

5 Claims. (Cl. 277—21)

1

This invention relates to a valve structure and more particularly to such a structure which is adapted to the foot control of a pneumatic tool.

This application is a division of my copending application, Serial No. 472,020, filed January 11, 1943 which is now abandoned.

An object of this invention is to provide a new and improved valve structure for the control of a pneumatic tool and arranged for foot actuation, so that both of the operator's hands are free for other work.

Another object of this invention is to provide an improved valve structure which is quickly and easily operable to two operating positions and which requires definite actuation for operation from one position to the other.

Another object of this invention is to provide a reliable valve structure for foot operation which is particularly acceptable to mass production and sale at low cost.

Other objects and advantages will become apparent in the following description and from the accompanying drawings in which:

Figure 1 is a top plan view of a preferred embodiment of this invention and shows its adaptation to the control of a fluid pressure operated device.

Fig. 2 is a sectional view on an enlarged scale of the preferred valve structure and is taken substantially on a line 2—2 of Fig. 1.

Fig. 3 is a sectional view through a portion of the valve structure and is taken substantially on a line 4—4 of Fig. 2.

While the invention is susceptible of various modifications and alternative constructions, I have shown in the drawings and will herein describe in detail, the preferred embodiment, but it is to be understood that I do not thereby intend to limit the invention to the specific form disclosed, but intend to cover all modifications and alternative constructions falling within the spirit and scope of the invention as expressed in the appended claims.

Although the use of the valve structure to which this invention pertains is not necessarily so limited, it is illustrated and described herein in its adaptation to the control of a bench vise; this illustrative adaptation serving to disclose more fully the features of the invention.

In certain types of bench operations wherein a vise is used, the rate of production may be materially increased if the operator has both hands free while closing or opening the vise. For example, in second operations wherein such steps as hand filing, drilling, boring, tapping, or mill-

2

ing operations, are performed on a piece of work, the operator can replace a piece of work in a vise much more rapidly if both the hands are free to hold the workpiece or properly adjust its position as he secures the work in the vise. It is in such an environment that the present invention is extremely useful, although of course its utility is not limited to this field.

The novel features of the particular vise here illustrated (Fig. 1) are the subject matter of my earlier filed application Serial No. 472,020, of which this application is a division. Accordingly, the construction of the vise as such will only be briefly summarized before turning to the controller therefor which constitutes the illustrative embodiment of the present invention.

Referring particularly to Fig. 1 of the drawings, the vise includes a base 10 having side flanges 11 through which it may be secured to a work bench and has an abutment 12 providing the fixed jaw of the vise. The upper surface of this jaw is provided with tapped holes 13 for assembling fixtures thereon. At its other end a hollow casing 14 on the base provides a housing for the operating parts of the pneumatic actuator. The base is traversed by a bottom groove 16 and has upper surfaces 17 which receive a slidable block 18 constituting the movable jaw. The block has a portion 19 extending into the recess 16. The block or movable jaw 18 slidably engages surfaces on the base. The portion 19 similarly engages inwardly facing surfaces on the base sections and guides the longitudinal movements of the movable jaw.

Both the fixed and movable jaws 12, 18 may have hardened face plates 23 secured thereto, which may be provided with opposed grooves 25 complementary to the workpiece. As a safety measure, a hardened block 26 may be secured to the base to limit the closing movement of the movable jaw. The movable jaw is operated by a pneumatically actuated diaphragm type motor which is enclosed in the hollow casing 14 which casing has an inner end 27 located with the axis of its bore 28 in substantial alignment with a central portion of the movable jaw. The housing flares outwardly as at 29 and an end cap 32, secured thereto by screws 34, closes the end of the casing 14 and covers an actuating diaphragm (not shown). Compressed air is admitted to the space between the cap and the diaphragm through a port 36 arranged for connection with a compressed air conduit 37.

A piston or ram 40 is actuated by the diaphragm and has a stem 42 which extends through the

bore 28 in the end 21 of the housing. A keyway 43 in the housing end 27 is provided for loose engagement with a key 44 on the stem to restrain the stem against rotational movement. The stem has an axial bore which is threaded for engagement by an end 51 of an adjusting screw 52. The screw extends into a recess in the movable jaw 19 and is suitably secured thereto for relative rotary but non-axial movement by a set screw 54. The screw 52 has a finger wheel 56 secured thereto and any relative position of adjustment between the adjusting screw and piston stem is fixed by a lock nut 57. Thus, the open position of the movable jaw may be so adjusted as to provide just the clearance required for the insertion of a given workpiece.

Novel means is provided for enabling the operator to control the actuation of the vise with his foot, thus freeing both of the operator's hands for holding or adjusting the workpiece as it is clamped in or removed from the vise.

Referring to Figs. 1, 2 and 3, the foot controller illustrated herein embodies a base 58, arranged to rest upon the floor. The base is rectangular in shape and has about the average dimensions of an operator's foot. A valve body 60 is secured, as by screws 59, near one end of the base with its long dimension extending transversely of the base. The valve body has a longitudinal bore therein which may, for convenience, be considered as having two end portions 61, 62 and an intermediate portion 63 of lesser or restricted diameter defined at its ends by outwardly facing shoulders 64, 65 providing valve seats. The valve member is slidably mounted in the bore end, as shown, comprises a stem 66 having valves 67, 68 mounted on the opposite ends thereof. The stem is arranged to extend through the restricted intermediate portion 63 of the bore and is flattened (as shown) or otherwise suitably formed to provide clearance for the passage of fluid between the stem and the casing. The stem is longer than the intermediate bore portion 63 so that the valves 67, 68 are only capable of alternate engagement with their respective valve seats 64, 65.

There are three ports 69, 70 and 71 (Fig. 3) in the valve body communicating respectively with the bore portions 61, 63 and 62. The ports 69, 70 are respectively connected through nipples 72 with a conduit 73 (Fig. 1) leading to a suitable source of pressure fluid (not shown) and with the conduit 37 to the pressure chamber of the vise actuating diaphragm motor. The ports 69, 70 are separated by the valve 67 which thus controls the flow of pressure fluid to the motor. Port 71 is an exhaust port leading to atmosphere from the end portion 62 of the bore. It is separated from the outlet 70 by the valve 68, so that this valve controls the exhaust of pressure fluid from the motor.

The end portion 61 of the bore is closed by a screw threaded plug 74 and a spring 75 interposed between the plug and the valve 67 exerts its force normally to urge the valve 67 toward its seat 64 and the valve 68 away from its seat 65. The line pressure exerted against the head of valve 67 normally holds the valve assembly in this position in which communication between ports 69 and 70 is normally closed and the latter is normally vented to atmosphere through port 71. The opposite end portion 62 of the bore is arranged slidably to receive an actuating plunger 76 or the like variably bearing against a spring 77 (which may be substantially heavier than the spring 75) interposed between the valve 68 and the inner end of

the plunger 76. The outer end of the plunger is preferably rounded.

The valve structure is concealed within an enclosing case 78 including a flat, generally rectangular plate or upper wall member 79 upon which the operator's foot may rest, and having a depending marginal flange forming side walls 80, which between their ends are inwardly offset as at 81 (Fig. 1) to provide clearance for transversely spaced upstanding bosses 82 on the base. A pintle 83 carried by the bosses extends through the side walls 80 pivotally supports the case on the base for rocking movement about an axis located at one side of and substantially parallel to the axes of the plunger 76 and valve member 66. The case 78 constitutes a means for actuating the plunger 76 and for this purpose, the portion of the side wall, which in assembly is opposite to the outer end of the plunger 76, carries, as shown in Fig. 2, a cam 84 having a rising surface 85 and a flat surface 86 which successively engage the rounded end of the plunger as this end of the case is rocked downwardly. The cam surface 85 is adapted to move the plunger inwardly to compress the spring 77 until its force is sufficient to overcome the holding force exerted primarily by line pressure and in part by the opposite spring 75, thereby to shift the valve member to close the valve 68 and open the valve 67. The parts are held in this relationship by the engagement of the flat surface 86 of the cam with the plunger until the case is intentionally reversely rocked.

When the plunger has been shifted to open the valve 67 and close the valve 68, pressure fluid is admitted to the diaphragm motor through the conduit, ports and passages 73, 69, 61, 63, 70, 37 and 36. Pressure fluid moves the piston or ram to the left as shown in Fig. 1, thereby shifting the movable jaw 19 into clamping engagement with a workpiece disposed between the jaws. When the operator rocks the case 80 of the controller in the reverse direction, the plunger 76 is released to permit the line pressure and spring force to return the parts instantly to their normal positions in which the valve 67 is closed to cut off the diaphragm motor from pressure and vent it to atmosphere through open valve 68 and port 71.

It will be evident from the foregoing that a novel foot controller has been provided which is simple in construction and efficient in operation. It will be noted that after the operator has depressed one end of the case to open the valve and clamp the jaws on a workpiece, the parts of the foot controller will remain in that relationship until the case is intentionally rocked in a reverse direction. Thus the user need have his foot on the foot controller only when he intends to manipulate it.

60 I claim as my invention:

1. In a foot controller for a pressure fluid actuated device, the combination of a base, a valve casing mounted on said base, said casing having therein a valve operable by linear motion to two operating positions, means comprising a resilient member biasing said valve to one of said positions, an actuating member movable linearly and adapted to effect movement of the valve against the normal biasing force to the other of said operating positions, said actuating member having a cam surface, an operating member providing a protecting cover for the valve casing and supported for rocking movement, and said operating member having a pair of cam surfaces thereon in cooperative relation with the cam surface

of said actuating member, one of the cam surfaces on said operating member being adapted to move said actuating member to effect operation of the valve, and the other of said cam surfaces on said operating member being adapted to hold said actuating member in a fixed position.

2. In a foot actuated controller for a pressure fluid operated device, the combination with a base, of a valve mounted on said base, a valve member in said valve shiftable between two positions to control the supply of pressure fluid to the device, spring means yieldably urging said valve member toward one of said positions, a plunger at one end of said valve operative when actuated to shift the valve member to the other of said positions against the action of said spring means, actuating means for said plunger including a member mounted on said base to rock about an axis located at one side and substantially parallel to the axes of said plunger and said valve member, and a cam element carried by said rocking member for coaction with said plunger.

3. In a foot actuated controller for a pressure fluid operated device, the combination with a base, of a valve mounted on said base, a valve member in said valve shiftable between two positions to control the supply of pressure fluid to the device, spring means yieldably urging said valve member toward one of said positions, a plunger at one end of said valve operative when actuated to shift the member to the other of said positions against the action of said spring means, actuating means for said plunger including a flat generally rectangular member having a depending marginal flange adapted to extend over said valve, means coacting with said flange to support said member for pivotal movement about an axis located at one side of and substantially parallel to the axes of said plunger and said valve member, and cam means carried by said flange for actuating said plunger.

4. In a foot actuated controller for a pressure fluid operated device, the combination with a

valve having an operating plunger projecting at one end, a rigid base supporting said valve, actuating means for said plunger including an actuating member having a depending marginal flange defining spaced side walls adapted to straddle said valve and said plunger, means supporting said member on said base for movement toward and from said valve, and means on one of said side walls engageable directly with said plunger in such movement of the member to actuate the same.

5. In a foot actuated controller for a pressure fluid operated device, the combination with a control valve having an operating plunger projecting at one end, of a rigid base supporting said valve, actuating means for said plunger including a member having a depending marginal flange defining spaced side walls, a pair of upstanding bosses on said base spaced from said valve and adapted to receive said side walls between them, a pintle extending through said bosses and said walls supporting said member for pivotal movement, and cam means formed on the flange of said member engageable with said plunger incident to such pivotal movement to operate the valve.
